(57) **CLAIM**

The ornamental design for a wall clock as shown and described.

DESCRIPTION

FIG. 1 is an isometric front right side view of a wall clock. FIG. 2 is an isometric front right side view of the wall clock with a glass cover in place.

FIG. 3 is a front view of the wall clock.

FIG. 4 is a front view of the wall clock with the glass cover in place.

FIG. 5 is a rear view of the wall clock.

FIG. 6 is a right side view of the wall clock, the left side view being a mirror image thereof; and,

FIG. 7 is a top view of the wall clock, the bottom view being a mirror image thereof.

The oblique lines on the glass cover disclosed in FIGS. 2 and 4 show a transparent surface.

The broken lines in the drawings illustrate portions of the wall clock that form no part of the claimed design.
